UNITED STATES PATENT OFFICE

2,322,069

RELAY

Allen G. Stimson, Lynnfield, Mass., assignor to
 General Electric Company, a corporation of
 New York

Application April 18, 1942, Serial No. 439,508

5 Claims. (CL 200—88)

My invention relates to relays and more specifically to overload relays of the type having a thermo-sensitive magnetizable portion responsive to heat generated by a current flowing in the circuit to be protected.

A number of thermo-sensitive magnetic materials having the property of changing their magnetic permeability in a nonlinear manner with changes in temperature are well known to those skilled in the art. Certain metal alloys have this property to a marked degree, notably certain alloys of nickel, such as nickel-copper and nickel-iron alloy.

In the application of such an alloy to electric relays there are certain inherent difficulties which must be either overcome or minimized. In the first place, thermo-magnetic alloys are at best only about one-half as permeable as soft iron. Furthermore, while the total change of permeability with temperature is sufficiently large to be effective, the maximum rate of change is not sufficiently rapid to produce the desired speed of relay operation. My overload relay, while simple and rugged in structure, is inexpensive to manufacture and minimizes the adverse effects of the above properties of thermo-magnetic material.

Accordingly it is an object of my invention to provide an electric overload relay of the thermo-magnetic type which shall be inexpensive to manufacture, of simple and rugged construction, and efficient, reliable and durable in operation.

It is a further object of my invention to provide an electric overload relay using inexpensive thermo-magnetic wire as the temperature sensitive element.

It is a still further object of my invention to provide an electric overload relay having a special type snap action for operation in conjunction with a sensitive element consisting of thermo-magnetic wire.

According to a preferred form of my invention, I provide a movable switch member including a small permanent magnet of relatively high coercive force in combination with a fixed keeper formed of a closely wound coil of thermo-magnetic wire having convolutions so disposed that at least a portion of each convolution lies longitudinally in the path of magnetic flux between the pole faces of the magnet. Means are provided for biasing the permanent magnet to a contact disengaging position, but under normal operating conditions the biasing force is resisted and the magnet releasably retained in a contact engaging position by the magnetic attraction of the magnet for its thermo-magnetic current carrying keeper coil.

For a more complete understanding of my invention and a further appreciation of its objects and advantages, reference should now be had to the following detailed specification taken in con-

junction with the accompanying drawing in which Fig. 1 is a side elevation of an overload relay embodying my invention, certain parts being broken away to show the internal structure; Fig. 2 is a cross-sectional view taken along the line 2—2 of Fig. 1; Fig. 3 is a plan view of the device of Fig. 1; Fig. 4 is a perspective view of the permanent magnet and thermo-magnetic keeper; and Fig. 5 is a cross-sectional view of an electric overload relay embodying the principles of my invention in a modified form.

Referring now to the drawing, and particularly to Figs. 1 to 4 inclusive, my overload relay in one form comprises a hollow substantially cylindrical casing 10 of suitable insulating material, such as a molded plastic compound, provided at one end with a removable circular closure plate 11 of insulating material and formed exteriorly to provide a plurality of pairs of radially extending bosses 12 and 13. The circular end plate 11 is held against outward displacement by a plurality of radially inwardly extending ears 14 formed upon the casing 10 and is manually movable longitudinally inwardly of the casing 10 to serve as a reset button in a manner to be more fully explained hereinafter. The pair of external bosses 12 is fitted with a pair of terminal connectors 15 which provide external electrical connection to a pair of stationary contact members 16.

The cylindrical casing 10 is slotted longitudinally, as at 17 and 18, slidably to accommodate a diametrically disposed bridging contact 19 which is normally biased into engagement with the fixed contacts 16 by a relatively light compression spring 20 disposed between the bridging contact 19 and the end plate 11 of the relay casing. Beneath the bridging contact 19 there is slidably mounted within the casing 10 a small permanent magnet 25 having attached at one end thereof, as by a bolt 26, an overhanging circular cap 27 of insulating material. Thus the spring 20 maintains the bridging contact 19 constantly in following engagement with the magnet 25. A helical compression spring 28 surrounding the magnet 25 and disposed between an annular shoulder 29 on the cap 27 and an annular shoulder 30 formed on the casing 10 biases the entire movable switch member, comprising the magnet 25, cap 27 and the bridging contact 19, to a contact disengaging position against the biasing force of the relatively light followup spring 20.

As best shown at Fig. 4, the permanent magnet 25 is of substantially cylindrical configuration having one end slotted diametrically as at 25a. Adjacent sides of the magnet are oppositely magnetized in the manner of a U-shaped or horseshoe magnet thereby forming a pair of substantially semicircular pole faces 25b and 25c of opposite polarity lying in the same plane. In order to obtain sufficient coercive force while lim-

iting the physical proportions of the magnet, I prefer to form the magnet 25 of an alloy comprising 6 to 15% aluminum, 12 to 30% nickel, about 5% copper, if desired, and the remainder of iron, such as described and claimed in Patents 1,947,274 and 1,968,569, issued February 19 and July 31, 1934, respectively, to William E. Ruder.

Each of the pair of external bosses 13 on the casing 10 is fitted with a cylindrical externally knurled and internally threaded bushing 31 arranged to support a flat coil spool 32 at the open end of the casing 10 in parallel spaced relation to the plane of the pole faces 25b and 25c of the magnet 25. The bushings 31 are provided with bolts 33 forming terminal connectors for a coil 34 formed of thermo-magnetic wire and wound upon the flat spool 32.

The flat spool 32 is composed of insulating material and, as best shown at Fig. 4, is substantially rectangular in shape and provided with a pair of diagonally disposed outwardly extending lobes for connection of the spool to the relay base. As illustrated to advantage at Fig. 1, the lobes of the insulating spool 32 are bolted to the extending ends of a pair of electrically conducting metal plates 35 which are inset in the bosses 13 and riveted to the bushings 31. The bolts 36 which serve to mount the spool 32 also clamp a pair of lead wires 34a and 34b from the coil 34 between the plates 35 and the lobes of the spool 32.

The coil 34 which is preferably substantially flat, is best illustrated at Fig. 4, and is formed of a plurality of closely wound convolutions of thermo-magnetic wire which has the property of undergoing a nonlinear decrease of magnetic permeability as its temperature is increased. In order to insure minimum reluctance between the pole faces 25b and 25c of the permanent magnet the coil 34 is preferably mounted for direct engagement with the pole faces to serve as a fixed magnet keeper and is so disposed that one of the longer sides of each turn or convolution of the coil lies substantially longitudinally of the path of magnetic flux between the pole faces of the magnet when the magnet is in its contact engaging position.

From the foregoing detailed description of the various elements of my device and the manner of their assembly, it is believed that the mode of operation will be evident from the following brief description.

Referring particularly to Figs. 1 and 2, the relay is shown with the movable switch member in its normal or circuit closing position wherein the permanent magnet 25 is magnetically retained in engagement with the keeper coil 34 against the circuit opening bias of the compression spring 28. It will be understood that current of a load circuit to be protected or a current proportional thereto is passed through the thermo-magnetic keeper coil 34 by connection of the circuit to the terminal connectors 33, and that the contacts 16 and 19 are connected through the terminal connectors 15 in a suitable manner to enable them to disable the load circuit upon their disengagement. If now the current in the load circuit and, consequently the current traversing the keeper coil 34, exceeds a predetermined excessive value the heat generated in the coil 34 will be sufficient to cause a marked and relatively rapid decrease in the permeability of the coil 34 so that the force of magnetic attraction between the coil 34 and the permanent magnet 25 will diminish to a point where it is exceeded by

the biasing force of the compression spring 28. Since the spring 20 also opposes the spring 28, it will be evident that the force of magnetic attraction must decrease to a point where the sum of the magnetic force and the force of the spring 20 is less than the force of the spring 28. Under such conditions the spring 28 will disengage the magnet 25 from the keeper coil 34 and will move the magnet and bridging contact 19 quickly to a circuit opening position. In order that this operation might be carried out with the desired snap action, it is necessary that the gradient of the spring 20 be less than the combined gradient of the spring 28 and the force of magnetic attraction. If the spring 20 is too stiff the opening movement will take place slowly.

The relay as described inherently tends to reset automatically, since a decrease in temperature of the keeper coil 34 increases its permeability and increases the magnetic attraction between it and the magnet 25. It has been found preferable, however, to forego the advantages of automatic resetting operation by operating the device on a differential too wide to permit resetting, thereby to obtain a more dependable snap action upon contact disengaging movement. It is to provide for manual resetting that I have arranged the end plate 11 of the casing 10 for inward movement against the combined force of the compression springs 20 and 28. By pressing the end plate 11 inwardly the magnet 25 is forced into engagement with the keeper coil 34 and, if this coil has cooled sufficiently, the force of magnetic attraction between the coil and the magnet will maintain the magnet in its contact engaging position.

At Fig. 5 I have shown a modified form of my invention in which a permanent magnet 50 is resiliently and pivotally mounted upon a leaf spring 51 for movement through an aperture 52 in a base 53 of suitable insulating material. The leaf spring 51 is mounted upon a relatively rigid supporting bracket 54 and is biased to a circuit opening position by a light spring strip 55. At one end the leaf spring 51 carries a movable contact 56 for engagement with a stationary contact 57, and intermediate its ends is mounted a permanent magnet 50 set in a molded cup 58 of suitable insulating material which serves to insulate the magnet 50 from the contact spring 51. On the under side of the base 53 and opposite the leaf spring 51 is rigidly mounted a flat spool 59 of insulating material which serves to support a keeper coil 60 formed of a plurality of convolutions of thermomagnetic wire. As previously described in connection with the device of Fig. 1, the convolutions of the coil 60 are so disposed with relation to the poles of the magnet 50 that at least one of the longer sides of each turn or convolution forms a part of and extends in the direction of the magnetic path between the pole faces of the magnet 50. The device of Fig. 5 functions in substantially the same manner as that of Fig. 1, and it is believed that its mode of operation will be sufficiently clear from the previous description with reference to Fig. 1.

While I have shown and described certain preferred embodiments of my invention by way of illustration, many other modifications will be apparent to those skilled in the art, and I, therefore, wish to have it understood that I desire by the appended claims to cover all such modifications as fall within the true spirit and scope of my invention.

What I claim as new and desire to secure by Letters Patent of the United States is:

1. An overload relay comprising in combination, a hollow cylindrical base of insulating material closed at one end, fixed contacts mounted upon said base, a movable bridging contact extending diametrically of said base, a U-shaped permanent magnet slidably mounted within said base to actuate said bridging contact, spring means for biasing said bridging contact into following engagement with said magnet, a helical spring surrounding said permanent magnet and engaging said base to bias said magnet to a contact disengaging position, a substantially flat coil of thermo-magnetic wire wound upon a flat spool of insulating material fixedly attached to said base and disposed opposite the closed end thereof normally to engage the pole faces of said magnet as a keeper for releasably retaining said magnet in a contact engaging position, said coil comprising a plurality of convolutions one of the longer sides of each of which extends substantially longitudinally of the path of magnetic flux between said pole faces when said magnet is in said contact engaging position, and means for supplying electric current to said coil to heat said wire, whereby with loss of magnetic permeability said keeper coil releases said magnet with a snap action to disengage said contacts.

2. An overload relay comprising in combination, a hollow cylindrical base of insulating material, a pair of fixed contacts mounted upon bosses formed exteriorly of said base, a manually operable reset button forming a disc-shaped end wall for said cylindrical base, said reset button being movable into said cylindrical base and being provided with stops limiting outward movement thereof, a movable bridging contact diametrically disposed with respect to said cylindrical base to engage said fixed contacts, said bridging contact being slidable longitudinally of said base, a U-shaped permanent magnet slidably mounted within said base, a compression spring disposed between said bridging contact and said reset button to hold said bridging contact in following engagement with said magnet, a helical spring surrounding said permanent magnet and engaging said magnet and said base to bias said magnet to a contact disengaging position, a substantially flat coil of thermo-magnetic wire wound upon a flat spool of insulating material fixedly attached to said base and disposed at the end opposite said reset button, said coil normally engaging the pole faces of said magnet as a keeper for releasably retaining said magnet in a contact engaging position and comprising a plurality of convolutions one of the longer sides of each of which extends substantially longitudinally of the path of magnetic flux between the pole faces of said magnet, the gradient of said compression spring being less than the combined gradients of said helical spring and said magnet, and means for supplying electric heating current to said coil and said wire, whereby due to decrease of its magnetic permeability said keeper coil releases said magnet with a snap action to disengage said contacts.

3. An overload relay comprising in combination, a hollow cylindrical base of insulating material closed at one end, a fixed contact mounted upon said base, a U-shaped permanent magnet slidably mounted within said base, a movable

contact mounted for actuation by said magnet into and out of engagement with said fixed contact, a helical spring surrounding said permanent magnet and engaging said base to bias said magnet and said movable contact to a contact disengaging position, a keeper of thermo-magnetic material fixedly attached to said base and disposed opposite the closed end thereof normally to engage the pole faces of said magnet and releasably to retain said magnet in a contact engaging position, and electric heating means for heating said keeper to reduce its magnetic permeability, whereby with loss of permeability said keeper releases said magnet with a snap action to disengage said contacts.

4. An overload relay comprising in combination, a hollow cylindrical base of insulating material closed at one end, fixed contacts mounted upon said base, a movable bridging contact extending diametrically of said base, a U-shaped permanent magnet slidably mounted within said base to actuate said bridging contact, a helical spring surrounding said permanent magnet and engaging said base to bias said magnet and said bridging contact to a contact disengaging position, a substantially flat current conducting keeper of thermo-magnetic material fixedly attached to said base and disposed opposite the closed end thereof normally to engage the pole faces of said magnet for releasably retaining said magnet in a contact engaging position, and means for supplying electric heating current to said keeper to reduce the magnetic permeability thereof, whereby with loss of permeability said keeper releases said magnet with a snap action to disengage said contacts.

5. An overload relay comprising in combination, a hollow cylindrical base of insulating material, a pair of fixed contacts mounted upon bosses formed exteriorly of said base, a manually operable reset button formed to provide a disc-shaped end wall for said cylindrical base, said reset button being movable into said cylindrical base and being provided with stops limiting output movement thereof, a movable bridging contact diametrically disposed with respect to said cylindrical base to engage said fixed contacts, said bridging contact being slidable longitudinally of said base, a U-shaped permanent magnet slidably mounted within said base, a compression spring disposed between said bridging contact and said reset button to hold said bridging contact in following engagement with said magnet, a helical spring surrounding said permanent magnet and engaging said magnet and said base to bias said magnet to a contact disengaging position, a current conducting keeper of thermo-magnetic material fixedly attached to said base and disposed at the end thereof opposite said reset button, said keeper normally engaging the pole faces of said magnet releasably to retain said magnet in a contact engaging position, the gradient of said compression spring being less than the combined gradients of said helical spring and said magnet, and means for supplying electric heating current to said keeper to reduce the magnetic permeability thereof, whereby due to decrease of its permeability said keeper releases said magnet with a snap action to disengage said contacts.
